CUSHION FOR BILLIARD OR POOL TABLES.

1,115,761.

Specification of Letters Patent.

Patented Nov. 3, 1914.

Application filed July 26, 1913. Serial No. 781,308.

To all whom it may concern:

Be it known that I, MORTON L. ADLER, a citizen of the United States, and a resident of New York, in the county of New York and State of New York, have invented certain new and useful Improvements in Cushions for Billiard or Pool Tables, of which the following is a specification.

This invention relates to cushions for billiard or pool tables, and the objects of the invention are to improve the accuracy and speed of such cushions, so that the same will be faster and more accurate than those now in use.

To the accomplishment of the above objects and to such others as may hereinafter appear the invention comprises, a cushion having a relatively flat working face, provided with a flat reinforcing strip behind the working face of the cushion, said flat reinforcing strip being arranged to be acted upon by two other reinforcing strips placed behind the same.

Referring to the drawings: Figure 1 shows a vertical section of so much of a billiard table, with a ball resting on the bed thereof and barely in contact with the cushion, as is necessary to be shown to illustrate my invention. Fig. 2 is a view similar to Fig. 1, but showing the ball forced into the cushion. Fig. 3 is a view similar to Fig. 2, but showing the ball forced still farther into the cushion.

In the drawings, A is the cushion strip, composed of any suitable compound or material such as rubber suitable for the purposes of a billiard cushion, which is secured to the wooden lining B of the cushion-rail C. The cushion-rail is provided with a top-rail D and is secured to the bed E of the table in the usual manner. The cushion strip A and the lining B are usually covered with suitable cloth one end of which is tacked to the bottom of the lining B and the other end held in place by the retaining strip F, about which the end of the cloth is wrapped. The bed of the table is also usually covered with suitable cloth stretched over its top surface.

In the present instance the cushion strip A, as shown, is triangular in cross section and provided with a relatively flat working face G, which is slightly inclined inward from its upper edge, a little oblique to a

vertical plane that is located, relatively to the table-bed, so that the ball first contacts, at a point below the top of the working face and above the level of the ball center. When the ball is played against the working face, made as just described, the initial point of contact, while above the level in which lies the center of the ball, is considerably below the top edge of the working face, and when the surface of the ball comes into forcible contact with the whole extent of said face, the cushion face will react on the ball at a point considerably below the center, thus tending to repel the ball in substantially a horizontal direction.

A cushion such as described with a flat working face is very effective in taking the twist imparted to the ball, which is known as "English," and will permit of the use of balls that vary in size.

In order to get greater resiliency to a cushion of this flat working face type, it has been found desirable to arrange, in the rear of the working face, a series of reinforcing strips, these strips being arranged in such a manner that the increased resiliency given to the ball, by the action of the strips, will not affect the angles of incidence and reflection of the path of the ball when driven into the cushion.

In the present instance the reinforcing strips are three in number and are preferably made of thin flat metal ribbons designated by the letters K L and M. These flat ribbons or reinforcing strips are, in the present instance, approximately of the same width as the working face G of the cushion, in which they are embedded, it being customary to cover the strips with canvas or other suitable material, to hold the same in place and prevent the cutting of the cushion.

The reinforcing or operating strip K is, in the present instance, preferably placed so that it will be substantially vertical to the plane of the bed of the table, the lower edge, as shown, extending a little below the lower edge of the working face G, the face of the strip K being spaced away from the working face, in the present instance, approximately half its width, or about an eighth of an inch. The action of the flat operating strip K is very effective when the ball is driven with ordinary speed against the cushion, the flat

working face G permitting the placing of the strip K, as shown, so that the ball will be forced substantially horizontal along the surface of the bed of the table, without 5 wedging the ball downward against the table immediately after hitting the cushion, as is the case with a sharp edged cushion now generally in use. The flat operating strip K is very uniform in its action as its 10 flat surface affords a more uniform resiliency than strips made of wire or similar material. When the ball is driven into the cushion with considerable speed it has been found necessary to control the action of the 15 operating strip K and this is done, in the present instance, by means of flat metal ribbons or controlling strips L and M. These controlling strips are, in the present instance, approximately of the same width as 20 the operating strip K, and are placed at a converging angle toward the center of the operating strip K, as shown, so that the converging edges will be, as in the present instance, approximately three thirty-seconds 25 of an inch apart and away from the face of the operating strip K. It will be noticed that the controlling strip M is placed a little more nearly a vertical angle than the controlling strip L; the purpose of which 30 will be presently described.

When the controlling strips L and M are suitably embedded in the cushion, as above described, it will be seen that when the operating strip K is forced back, by a ball driven 35 into the cushion with considerable speed, the strip K will compress the rubber adjacent the ends of the controlling strips L and M, thereby tilting the strip K inward at its lower end so that the force imparted to the ball will be a little downward so as to keep 40 it from jumping off the table. This inward tilting of the bottom of the operating strip K, when a ball is driven into the cushion with considerable speed, is due to the fact 45 that the end of the controlling strip M yields more than the end of the controlling strip L, as the strip M is set at a more nearly vertical angle to the strip K than the strip L which is more nearly horizontal, and 50 therefore the strip M offers less resistance to the lower portion of the strip M, permitting the same to be tilted, as just described, by the end of the strip L. The operation of the strips are clearly shown in Figs. 2 and 3, 55 Fig. 3 showing the position of the strips when the ball is forced with considerable force against the cushion while Fig. 2 shows the action when less force is exerted.

The ordinary sharp edged cushion, now 60 generally in use, has many disadvantages when reinforced by means of metal strips and the like, for the reason that, due to its relatively sharp working face, it is necessary to place the reinforcing strips within

about $\frac{1}{2}$ of an inch from the working face, 65 with the result that there is very little material of the cushion between the reinforcing strip and the working face, in which the ball can embed itself for taking a proper angle either with or without twist, or English. The action of a reinforced sharp edged cushion is to prevent the embedding of the ball in the cushion, with the result that a ball driven into the cushion at an angle of say 70 degrees, will be thrust back 75 at an angle of about 90 degrees instead of at an angle of 70 degrees, which is a very undesirable feature. By experiment, I have found that a cushion provided with a flat faced working face, such as shown in the 80 drawings, will permit of the reinforcing strips being set back from the working face about again as far as in the case of a sharp edged cushion. This leaves a considerable amount of material, in addition to the 85 greater amount of contact surface provided by a flat working face in which the ball can embed itself for taking the correct angles so as not to be prematurely acted upon by the reinforcing strips being placed 90 too near the working face, as is the case with a sharp edged cushion.

In other words, it is absolutely necessary in order to have the ball take a proper angle from the cushion, to have the reinforced strips set at such a distance back from the working face that the ball can become sufficiently embedded in the cushion to accomplish this purpose. Due to the form of the ordinary sharp edged cushion it is 100 necessary to put the reinforcing strips very near the working face to get increased speed which results in false angles. A cushion provided with a flat working face permits the reinforcing strips to be set back a considerable distance from the working face, thereby leaving a considerable amount of material in which the ball can embed itself so that when the reinforced strip acts the ball will not be deflected from a true angle. 110

While the invention has been described with particular reference to the details of construction the same is not to be considered as limited thereto, as many changes can be made and still fall within the scope of the 115 invention set forth in the following claims.

What I claim is:

1. A cushion having a flat working face for billiard tables and the like comprising in combination a flat operating strip embedded in the cushion, flat controlling strips also embedded in said cushion at an angle to said operating strip for controlling the actions of the same. 120

2. A cushion having a flat working face 125 for billiard tables and the like comprising in combination a flat working strip embedded in the cushion adjacent said working

face and at right angles to the surface of the table, two flat controlling strips adjacent said operating strip, and arranged at a converging angle toward said operating strip, one of said controlling strips being set more nearly parallel to the operating strip than the other controlling strip.

In testimony whereof I have signed this specification in the presence of two subscribing witnesses.

MORTON L. ADLER.
